CLAIM

The ornamental design for a combined digital disc player and automotive navigation system, as shown and described.

DESCRIPTION

FIG. 1 is a perspective view of a combined digital disc player and automotive navigation system showing my new design;

FIG. 2 is a perspective view showing the monitor (the navigation device) detaching therefrom;

FIG. 3 is a front view of FIG. 1;

FIG. 4 is a left side view thereof;

FIG. 5 is a right side view thereof;

FIG. 6 is a top plan view thereof,

FIG. 7 is a front views showing the docking station without the monitor (the navigation device) thereof;

FIG. 8 is a sectional view thereof, taken along line 8—8 of FIG. 7; and,

FIG. 9 is a perspective view of FIG. 1 showing the front panel opening.

The broken line shown in FIGS. 1 to 9 is for illustrative purposes only and forms no part of the claimed design.
